UNITED STATES PATENT OFFICE

2,306,183

ELASTIC FLUID GENERATOR

Keiji Okaniwa, Yokohama, Japan, assignor to
General Electric Company, a corporation of
New York

Application October 23, 1940, Serial No. 362,391
In Japan January 17, 1940

1 Claim. (Cl. 122—444)

The present invention relates to elastic fluid generators or boilers, particularly to steam boilers with an economizer to preheat feed water or like operating liquid for the boiler.

An object of my invention is to provide an improved construction and arrangement of boilers whereby a maximum amount of available heat energy in the combustion gases is utilized to preheat and evaporate fluid in the economizer.

Another object of my invention is to provide an improved economizer whereby oxidation and scale formation in the heating tubes are reduced to a minimum.

For a consideration of what I believe to be novel and my invention, attention is directed to the following description and the claim appended thereto in connection with the accompanying drawing.

In the drawing, Fig. 1 illustrates diagrammatically a sectional view of a boiler embodying my invention, and Fig. 2 is a section along lines 2—2 of Fig. 1.

The arrangement comprises walls 10 and 11 forming a combustion chamber 12 and convection chambers 13 and 14. Fuel and combustion air are conducted to the combustion chamber by means including a burner 15 suitably supported on and projecting into the chamber 12. During operation, combustion gases formed in the chamber 12 are discharged therefrom through the series-connected convection chambers 13 and 14. The gases in the last convection chamber 14 are discharged to atmosphere through a stack 16 connected to the lower end of the chamber 14.

The boiler proper comprises banks of slanted heating tubes 17 having inlet portions located in the convection chamber 14 and connected to a header 18 and outlet portions located in the upper part of the combustion chamber 12 and connected to an outlet header 19. Water or like operating liquid is conducted to the inlet header 18 by a plurality of down-tubes 20 lining the wall 11 and having upper ends connected to the bottom portion of a drum 21. The liquid, on its path through the tubes 17, is heated and partly evaporated, and the mixture is discharged from the outlet header 19 through a plurality of up-tubes 22 lining another portion of the wall 11 and connected to the vapor space of the drum 21. An upper row of the tubes 17 has portions 23 bent upwardly and arranged to line a partition 24 between the convection chambers 13 and 14. The upper ends of the tube portions 23 are connected to the aforementioned tubes 22 to discharge the mixture of liquid and vapor formed in the tubes 23 into the drum 55

21. The elastic fluid is discharged from the drum 21 through a superheater 25 located in the convection chamber 13 and having an inlet conduit 26 connected to the vapor space of the drum and a discharge conduit 27 for connection to a consumer of elastic fluid.

Feed water or like operating liquid is supplied to the drum from a source, not shown, through a feed pump 28 and an economizer located in the convection chamber 14 and connected between the pump 28 and the drum 21.

The economizer in accordance with my invention comprises a first section 29 located near the stack 16, that is, near the outlet of the convection chamber 14, and a second section 30 located near the inlet of the convection chamber 14 and connected in series between the section 29 and the drum 21. The section 29 of the economizer comprises a plurality of parallel connected banks of tubes 31, 32 with each tube having a plurality of hairpin-shaped series-connected portions of relatively large diameter and outer finned surfaces. The tubes of the first section 29 are made of cast iron. They are of large diameter and closely spaced and, therefore, effect low velocity of the water through the tubes and comparatively high velocity of the combustion gases through the spaces formed between the tubes.

The second economizer section 30 also consists of a plurality of parallel connected tubes 33, each having a plurality of series-connected hairpin-shaped tube portions. The tubes 33 are made of steel and are of small inner diameter as compared to the inner diameter of the tubes 31, 32. In addition, the tubes 33 are comparatively widely spaced. Hence, the water or mixture of liquid and steam is forced through the tubes 33 at high velocity whereas the combustion gases pass through the spaces formed between the tubes 33 at comparatively low velocity.

The economizer is of the evaporation type, that is, a part of the liquid is evaporated in the second economizer section 29, the mixture of liquid and vapor being discharged into the vapor space of the drum 21. From the latter, the vapor is passed through the superheater 25, whereas the liquid is passed through the liquid heating and evaporating tubes 20, 17, and 22.

During operation of the boiler, scale-forming ingredients carried in the feed water discharged from the pump 28 are decomposed and precipitated in the first economizer section 29 and, at the same time, oxygen contained in the feed water is absorbed on the inner surface of the cast iron heating tubes 31, 32 of the first section. High

velocity of circulating water in the second economizer section together with the function of the first economizer section reduces oxidation and scale formation on the evaporating tubes of the second economizer section 29.

What I claim as new and desire to secure by Letters Patent of the United States is:

An elastic fluid generator comprising walls forming a combustion chamber and a convection chamber located adjacent the combustion chamber and having an end connected thereto to receive gases discharged from the combustion chamber, a drum, heating tubes located partly in the combustion chamber and partly in the convection chamber and connected to the drum and means including an economizer for supplying preheated fluid to the drum, the economizer having a first

section located near the outlet of the convection chamber on one side of the heating tubes and comprising a bank of closely spaced cast iron heating tubes of wide diameter and a second section 5 near the inlet of the convection chamber on the other side of the heating tubes and connected in series between the first section and the drum and comprising a bank of widely spaced steel tubes of small diameter to effect low velocity of the combustion gases through the spaces formed by the second section and high gas velocity through the spaces formed by the first section and also to effect low velocity of the operating fluid through the first section and high velocity of the operating fluid through the second section.
